TELEPHONE SYSTEM

Edson L. Erwin, Towaco, N. J., and Frederick R. Lamberty, Brooklyn, N. Y., assignors to Bell Telephone Laboratories, Incorporated, New York, N. Y., a corporation of New York

Application March 23, 1940, Serial No. 325,510

9 Claims. (Cl. 179—18)

This invention relates to telephone systems and particularly to small automatic systems in which connections are established through cross-bar switches.

An object of the invention is to improve and simplify such systems and expedite the establishing of connections and economically arrange and utilize common equipments.

Heretofore systems of this type have been arranged with common recorders, marker circuits and linking circuits for establishing connections between subscribers' lines and between trunks and subscribers' lines in which idle links and registers are seized and controlled by a common marker circuit to effect connections after which the recorder and marker circuits are reverted to common use.

It is a feature of the present invention to apply, in systems of this kind, common ringing and coin control circuit equipments that may be temporarily seized through cross-bar switch connectors to ring a called subscriber's line or to ring over a trunk and to release when the call is answered, or in case the calling subscriber's station is a coin station to ring a called subscriber's station, send a coin tone to the calling station when the called subscriber answers and release when the calling subscriber deposits a coin.

Another feature is a so-called by-link arrangement which is employed in line-to-trunk calls to establish a direct and temporary connection between a calling line and a desired trunk, while a permanent connection from the calling line through link circuits to the trunk is established over a trunk connecting cross-bar switch, or in case of trunk-to-line calls to establish a by-link connection temporarily and directly to a recorder, while a permanent connection is established from the trunk through a link circuit to the recorder over a trunk and register connecting cross-bar switch. The purpose of these temporary connections is to provide means whereby in case the permanent connection cannot be immediately established due to some delay in securing the use of the common marker circuit and idle link circuits, the dialing of a complete number from a calling subscriber's line or from a trunk need not be delayed or interrupted to wait for a second dial tone in case of line-to-trunk calls or in case of trunk-to-line calls to permit the transmission of the number immediately after the trunk is seized at a distant office.

The invention has been illustrated in connection with a system containing certain other in-

ventions covered by a copending application of E. L. Erwin, Serial No. 324,306, filed on March 16, 1940. The system contemplates the use of call originating switches of the cross-bar type, for establishing connections from calling lines to link circuits and of call terminating switches of the same type for establishing connections from said linking circuits to called lines, that is, all the lines appear as calling lines on call originating switches and as called lines on call terminating switches. Thus when a call is made a select magnet in a call originating switch is operated followed by the operation of a holding magnet to establish a connection from the calling line to a linking circuit and when the call is extended to a desired called line, a select magnet in the call terminating switch is operated followed by the operation of a hold magnet to establish a connection from said linking circuit to the called line. One of the features covered by said copending application relates to the arrangement in which the marker circuit for establishing connections between the subscribers' lines is so arranged that when a holding magnet in a call originating switch is operated, a holding magnet in the associated call terminating switch where the calling line also appears as a called line is operated and when a call terminating switch is to be operated for establishing a connection to the called line, a holding magnet in the associated call originating switch is first operated followed by the operation of the holding magnet in the call terminating switch. Other features relate to the utilization of these holding magnets for a calling subscriber lock-out arrangement on permanent signals and for the establishing of revertive calls on party lines.

This invention has been illustrated in the accompanying drawings in which

40 Figs. 1 to 27 show in detail a small automatic system using cross-bar switches and embodying the features of the present invention.

Fig. 28 shows an arrangement of the Figs. 1 to 27; and

45 Fig. 29 shows in diagrammatic form the general switching plan employed in this system.

If reference is made to Fig. 29, a description will be made of the switching plan in general. Call originating cross-bar line switches have been shown in two groups at 2900 and at 2901 with the subscribers' lines arranged as calling lines in vertical rows indicated by the vertical lines. At 2902 is shown a common group of call terminating cross-bar line switches, with the same subscribers' lines arranged in vertical rows indicated

by vertical lines. It will be noted that the first subscriber's line in the call originating switch group 2900 has been shown multiplied to the first line in the call terminating line switch group at 2902 and it is evident that all the other lines in the two types of switches are similarly multiplied. Linking circuits such as the groups 2903 and 2904 are shown by horizontal lines as terminating in the call originating switches 2900 and 2901, respectively. These linking circuit groups also terminate, respectively in so-called trunk and recorder switches 2905 and 2906 as horizontal lines. The vertical cross-lines in these trunk and recorder switches are divided into two groups, one group representing the terminating connections for the group of registers 2907 and the other group representing the terminating connections for the group of trunks 2908. The recorder and trunk groups also terminate in the by-link arrangement shown at 2910 as vertical lines although the by-links are not cross-bar lines but groups of relays and associated circuits. Returning now to the linking circuits, the two groups 2903 and 2904 terminate also in vertical lines in secondary cross-bar switches 2911. The horizontal lines of these secondary switches may be connected to a group of junctor circuits 2912 which also terminate as horizontal lines in the call terminating switches 2902. A group of ringing and coin control circuit connector switches is shown at 2914, the vertical lines of which have access to a group of ringing and coin control circuits 2915 and the horizontal lines of the left-hand ringing and coin control circuit connector have access to the group of trunks 2908, while horizontal lines of the middle and right-hand ringing and coin control circuit connectors have access to the junctors 2912.

With this arrangement of switches and linking circuits, junctors, recorders, trunks, ringing and coin control circuits and by-links, various types of connections may be established. A common marker circuit 2919 has been illustrated in the center of this diagram and lines leading from this marker circuit to the various switches and circuits indicate that this marker circuit is common to the system and may be used for controlling the establishing of connections.

To illustrate how various connections may be established by means of these devices typical calls will be traced through the diagram and marked by heavy lines. For example, a call may be established from a calling subscriber such as is indicated at 2920 through the call originating switch 2900 over an idle link through the trunk and recorder switch 2905 to an idle recorder. The selection of a recorder and an idle link circuit is controlled by the marker circuit 2919. When this connection is established dial tone is received by the calling subscriber and the marker circuit is released. The circuits being now ready for dialing, the calling subscriber dials the desired number, for example, the number of the desired subscriber such as 2921. This called subscriber's number is recorded in the seized recorder and when dialing is completed, the marker circuit is again seized and selects an idle junctor which has access to the section of terminating switches in which the called line is located. This is accomplished by the hundreds or first digit dialed into the recorder. When the junctor has been thus seized, the secondary switch 2911 is operated to connect this junctor to the line link to which the calling subscriber is connected. The tens and units or second and third digits

dialed into the register now control by the aid of the marker circuit the terminating line switches to connect the seized junctor to the called line 2921 and if the line is idle, a ringing and coin control circuit connector switch seizes an idle ringing and coin control circuit and the last or ringing code digit will operate this ringing and coin control circuit to transmit the desired ringing code to the called subscriber 2921 which, of course, may be one of several on a party line or a single line subscriber. When the subscriber 2921 answers this call, the ringing and coin control circuit is tripped and a talking connection is established whereupon the ringing and coin control circuit is released by the ringing and coin control circuit connector, while the recorder and marker are released as soon as the subscriber is rung. The connection between the subscribers 2920 and 2921 is marked in heavy lines as well as the connection to a recorder and a ringing and coin control circuit. In case the calling line is a coin line the arrangement is such that when the called subscriber answers a coin tone is transmitted to the calling station and when the calling subscriber deposits a coin the recorder, the marker circuit, the ringer and coin control circuit are dismissed.

If a connection is desired from the subscriber 2920 to a trunk, such as, for example, trunk 2922, which may be one of a group of trunks leading to a certain office, the calling subscriber establishes a connection as described through a recorder by the aid of the marker circuit and then dials the trunk code digit, that is, the first digit only indicating the office desired. When this digit has been dialed, one of the by-links in the group 2910, which has been previously automatically assigned for use, will immediately connect up the seized recorder to an idle trunk in the trunk group leading to the desired office. The marker circuit is then taken for use to control the connection of this trunk to the link to which the calling subscriber is connected through the trunk and recorder switch 2905 and the marker circuit, the by-link connection and the recorder are then released. The purpose of the temporary connection through a by-link is provided for the purpose of immediately establishing a connection to a desired trunk as soon as the trunk code digit is dialed so that the equipment at the distant end of the trunk may be prepared to receive the succeeding digits that may be dialed by the calling subscriber to establish a connection in the distant office without having to wait for the establishing of a permanent connection from the calling line through a link and the trunk through the trunk and recorder switch 2905. This connection for a trunk through a recorder, a by-link and a trunk and recorder switch over a link to a calling line has been shown in heavy lines.

In case a connection is desired from a trunk from a distant office such as trunk 2922 to a called subscriber such as 2921, a call incoming over the trunk 2922 immediately causes the seizure, through a preassigned by-link of an idle recorder and a dial tone is transmitted over the trunk. Dialing may then begin from the distant office over the trunk to register the called subscriber's number. The marker circuit is then immediately seized and selects an idle link which is then connected to the seized recorder and to the trunk through the trunk and recorder switch and the marker is then released. If the dialing has not been completed at this time, it will

be transmitted over this new connection to the recorder and the by-link connection will be released. The connection from this point on is the same as a call from a calling subscriber to a called subscriber, that is, the recorder will control the establishing of a connection from the trunk over the seized link through the secondary switch over a junctor through a line terminating switch to the called subscriber 2921. These connections are marked in heavy lines.

Referring now in general to the Figs. 1 to 27, arranged in accordance with Fig. 28, Fig. 1 shows two terminating switches T_1 and T_2 . Switch T_1 shows two subscribers' lines terminating therein and the switch T_2 shows one subscriber's line terminating therein with their respective holding magnets and select magnets for selecting idle junctors. Fig. 4 shows a call originating switch CO in which the two subscribers' lines shown in the terminating switch T_1 also are indicated with their respective holding magnets and select magnets for selecting idle links. The two link circuits L_1 and L_2 terminating in this call originating switch CO also terminate in Fig. 4 in the secondary switch SS and are extended to Fig. 9 to appear in a recorder and trunk switch RT. This recorder and trunk switch shows two connections to trunks and two to recorders one of each of which is completed through the succeeding figures. The trunk is shown complete in Figs. 14 and 19 and the recorder is shown complete in Figs. 15, 20, 21, 22, 23 and 27. Two by-links have been shown complete in Figs. 24, 25 and 26 and the common marker circuit has been shown in Figs. 10, 11, 12, 13, 16, 17 and 18 and parts of Figs. 5 and 6. One of the common ringing circuits has been shown complete in Figs. 3, 7 and 8, while in Fig. 2 the two link circuits L_1 and L_2 have been shown, L_1 in detail and L_2 indicated by a box. In Fig. 5 is shown a ringing circuit connector switch RC with cross-points for connecting the ringing circuit, shown in the Figs. 3, 7 and 8, to the link circuit L_1 or L_2 or to the trunk circuit shown in Figs. 14 and 19.

Descriptions will now be made in detail of the three types of connections as outlined in connection with Fig. 29 and in accordance with the layout in Figs. 1 to 27.

A description will first be made of a call from one subscriber's line to another. If it is determined that the subscriber A desires to establish a connection to subscriber B, the latter of which may be one of a plurality of subscribers on a common party line, the subscriber at A removes his receiver from the switchhook and thereby causes the operation of the line relay 100 over a circuit from battery and ground through the windings of this relay, contacts of the holding magnet 400 for this subscriber's line in the call originating switch CO, over the tip and ring conductors through the loop at the subscriber's set. Relay 100 in operating now identifies the calling line by the operation of a relay in the group selecting circuit shown in Fig. 6. For example, if this is one of the subscribers in a group of ten of a group of sixty and is located in the first group, the first group relay 600 will operate over a circuit from battery through contacts of relay 100, winding and make-before-break contacts of relay 600, corresponding contacts of the succeeding group relay of which 601 and 605 have been shown to ground at contacts of the common relay 606 for this group. Relay 600 in operating locks at its own contacts to ground and prevents other subscribers in the same group of ten

from calling by operation of their group relays such as 601 and 605. The common marker circuit shown is thereby seized for use in connection with the establishing of the connection between these subscribers. Relay 600 in operating causes the operation of relay 1000 from battery through the winding of this relay, winding and contacts of relay 600 to ground. Relay 1000 operates relays 1100 and 1200 and these last-mentioned three relays connect a number of leads through the marker circuit. The first result of the operation of these relays is the closing of a circuit for relay 1600 from battery through the winding of this relay, contacts of relays 1800, 1901, 1601, 1100 and 600 to ground. The operation of this relay prevents calls that are being terminated from having access to the marker. Relay 1600 closes a circuit for the operation of relay 1602 from battery through the winding of this relay, contact of relay 1700 and 1600 to ground. This relay in operating starts the selection of an idle recorder circuit and starts the choice of an idle link for connecting the calling line to an idle recorder through the call originating line switch CO and the trunk and recorder switch RT.

The selection of an idle recorder is accomplished by the operation of a relay 1001 on the operation of relay 1602 from battery through the winding of relay 1001, contacts of relays 1100, 1600 and 1602 to ground. Relay 1001 in operating connects the winding of a group relay for selecting an idle recorder. There may be, for example, eight recorders and the recorder selecting relay 1802 for the first recorder and relay 1803 for the last recorder have been shown with the intermediate six relays omitted. Idle recorders are recognized by a battery through the winding of a relay 2300 as shown in the recorder illustrated and connected to a lead BT while this lead is opened if a recorder is busy. The recorder selecting relays of idle recorders will all operate over a circuit from battery through the winding 2300, for example, if the recorder shown is idle, through contacts of key 2200, contacts of relays 2201 and 2700, 1001, 1100 and 1804, winding of relay 1802 which represents the idle recorder shown, and the contacts of relays 1600 and 1602 to ground. Relay 1802 now operates and similarly other relays in the recorder selecting relay group representing idle recorders will operate but immediately release as the first idle recorder is always chosen and in this case the first recorder is shown. The relay 1804 will now operate at contacts of relay 1802 and hence open the BT leads for the other idle recorders so as to release these other recorder selecting relays. Relays 1802 and 1804 lock through the contacts of relay 1802 to battery at 1805. Relay 2300 will not operate over the first circuit that received ground at contacts of 1602 due to the high resistance of the windings of the recorder selecting relays, but will operate as soon as relays 1802 and 1804 become operated over a ground at contacts 1602 through resistance 1706. The operation of relays 2300 closes various leads between the recorder and the marker circuit which are required for originating calls. Thus the recorder shown in the drawings is one that is selected for use in establishing this connection and the immediate result of the operation of relay 2300 is the operation of relay 2100 from battery through the winding of this relay, contacts of relays 2300, 1200 and 1600 to ground. Relay 2100 closes an obvious circuit for the operation of

relay 2202 and this in turn closes an obvious circuit for the operation of relay 2701 and also a circuit for a relay 1500 associated with the hundreds storing relays for the first digit and this circuit may be traced from battery through the winding of relay 1500, contacts of relay 2203 and 2202 to ground. The operation of relay 1500 prepares paths for storing the first digit on the hundreds storing relays as will be hereinafter described.

Returning now to the operation that follows on the operation of relay 1602 for the choosing of an idle link for connecting the calling line to the recorder in the call originating line switch CO and the recorder connecting switch RT, the immediate result of the operation of relay 1602 is the operation of a connecting relay 500 which it is assumed is associated with the first group of ten lines in which the calling line is located to identify the calling line and closes through a number of leads for this purpose. There is one of these relays such as 500 for each group of ten lines. The circuit for the relay 500 is from battery, winding of relay 500, contacts of relays 600, 606, 1100, 1600, 1602 to ground. Relay 1602 also operates relay 1003 and 1004 from battery through the winding of these relays, contacts of relays 1100, 1600, 1602 to assist in a selection of an idle line link. The operation of relay 1602 also operates the relay 1300 in the recorder for starting the identification of the calling line. The circuit for this relay extends from battery through the winding of relay 1300, contact of relays 1700, 1601, 1701 and 1602 to ground. This relay connects the ten line selecting relays of which the first, ninth and tenth relays have been shown and identified with numerals 1301, 1302 and 1303, respectively. If the calling line is assumed to be the first line in the first group of ten, relay 1301 will operate over a circuit from battery through the winding of this relay, contacts of relays 1300, 1100 and 500, and holding magnet 101 to ground at the contacts of the line relay 100 associated with the calling line. The operation of relay 1301 closes a circuit for the operation of relay 1701 from battery through the winding of this relay, normal contacts of the calling line identification relays 1303, 1302 and intermediate relays to the right-hand inner armature and front contact of relay 1301 to ground. Relay 1701 closes a locking circuit for itself through its inner right-hand armature and front contact to ground at relay 1602 and opens the circuit for relay 1300 which now releases. This locking ground is also extended for holding relay 1301 operated at the inner left-hand armature and front contact of relay 1701.

The next step will now be the operation of relay 900 to make a busy test on the sleeves of an idle line link. This relay is operated on the operation of relay 500 from battery through the winding of relay 900, contacts of relays 500, 1100, 1600 and 1602 to ground. This relay connects the test relays to test for idle links in a group of ten of which links L₁ and L₂ have been chosen. If link L₁ is idle, test relay 1305 will operate in the group of ten test relays of which the first and last test relays 1305 and 1306 have been shown, the intermediate relays have been omitted. Relay 1305 operates over a circuit from battery through a resistance, contacts of relays 1004, 900, 1003, 1100 and 1307, winding of relay 1305, contacts of relay 1602 to ground. It should be noted that the sleeves of busy line links are grounded

but that all the line links that are idle will operate their associated test relays over corresponding leads from battery through the resistances at the contacts of relay 1004. The operation of any one of these line test relays closes its own locking circuit to battery at 1805 and operates relay 1307 over an obvious circuit and this relay opens the original operating path for all of the idle link testing relays. The operation of the relay 1307 operates the selecting magnet associated with the lowest numbered operated test relay through a chain of contacts on these testing relays and as it is assumed that the lowest numbered link L₁ is idle, relay 1305 operated as mentioned and the circuit for the select magnet of this link will therefore be closed from battery through the select magnet 901, winding of this magnet, contacts of relays 900, 1100, 1305, 1814, 1604 and 1307 to ground. That is, link L₁ will be the one selected in this case. The associated select magnet 403 will, as noted, also be operated over this circuit in parallel with the select magnet 901. The select magnet 901 is associated with the recorder connecting switch RT and the select magnet 403 is associated with the call originating switch CO for the link L₁. The operation of select magnet 403 closes circuits for the operation of relay 902 which is associated with this particular line link group. The circuit for relay 902 is traced from battery through the winding of this relay, contacts of relays 1100 and select magnet 403 to ground. Relay 1606 will now operate from battery through the winding of this relay, contacts of relays 1600, 1701, 1100 and 902 to ground. Relay 1606 operates relay 1512 over a circuit not shown for purposes as will become apparent as the description proceeds. Now that the calling line has been identified and an idle link selected, the holding magnet 904 for associating this link with the selected recorder will operate from battery through the winding of this magnet, contacts of relays 900, 2300, 1200, 1606, 1601 and 1602 to ground, thus connecting link L₁ at the cross-point 906 to the recorder shown in the drawing. The calling line will also be connected to link L₁ by the operation of holding magnet 400 from battery through the winding of this magnet, contacts of relays 500, 1100, 1301, 1302, 1303 and 1606 to ground, thus connecting the calling line to the cross-point 405 to the link L₁. The operation of the holding magnet 400 opens the circuit for relay 100 which now releases and the connection established at the cross-point 405 closes a circuit for the operation of the relay 2101 from battery, right-hand winding of relay 2101, contacts of relays 2301, 2702, the cross-connection at 906, the link L₁, the cross-connection at 405 to the subscriber's loop at A, the cross-connection at 405, link L₁, cross-connection at 906, contacts of relays 2702 and 2301, the left-hand winding of relay 2101, contacts of relays 2203 and 2008 and the upper left-hand winding of the repeating coil 300 to ground. This supplies a dial tone to the calling subscriber through the repeating coil 300 from the ringing source 301 and operates relay 2101. The closure of the connection at 405 closes a connection for the operation of relay 2201 from battery through the winding of this relay, contacts of relays 2202, 2302, 2301, connections over the sleeve at cross-points 906 and 405 to the ground at relay 1606, over the circuit hereinbefore traced for the operation of magnet 400. Relay 2201 in operating locks to ground at contacts of relay 2112 and this ground, it will be noted, locks the holding mag-

net 400 independently of the original energizing circuit for this magnet and relay 2201, closes a circuit for the operation of the release relay 1700 from battery through the winding of this relay, contacts of relays 1806, 1608, 1200, 2300, 2203, 2704, 2703, 2201 to ground. Relay 1700 opens the energizing circuit for relay 1602 which now releases causing a number of the operated relays to be released causing the release of the marker circuit and prepares the circuits for dialing. The order of release of the various relays is as follows: 600, 1600, 1000, 1100, 1200. The release of relay 1200 releases the marker and the marker relays are released as follows: 1301, 1701, 900, 1305, 1307, the select magnet 901 for the switch RT and the select magnet 403 for the switch CO. This releases relay 902. The following relays are then released: 1003, 1004, 1001, 1802, 1803, 500, 2300, and finally the release relay 1700. The release of relay 2300 prepares the circuit for dialing.

It should be noted now that in the recorder, the relays 2100, 2202, 2701, 2200, 2201 and 1500 are operated, relay 2100 being held operated by relay 2101. The subscriber may now dial four digits, hundreds, tens and units digits and a digit for selecting the ringing code. The relay 2101 follows the impulses. On the first release of this relay as the first digit is dialed, relay 2100 releases causing the operation of relay 2102 over a circuit from battery through the winding of this relay, contacts of relays 2205, 2100 and 2701 to ground. Relays 2102 and 2202 are slow in releasing and hence remain operated during the dialing of a digit. This relay closes a circuit for the operation of relay 2103 from battery through the winding of this relay, contact of relay 2104, 2105, 2100, 2102 to ground at 2701. When the relay 2101 operates at the end of the first pulse, this relay causes the energization of relay 2100 and this in turn causes the energization of relay 2105 in series with relay 2103 from battery through the winding of this relay, contacts of relay 2104, 2103, left-hand winding of relay 2105, contacts of relay 2102 to ground at relay 2701. At the beginning of the second impulse, relays 2101 and 2100 release causing the operation of relay 2104 from battery through the winding of this relay, right-hand winding of relay 2105 and its right-hand armature and front contact, contacts of relays 2100, 2102 to ground at relay 2701. Relay 2104 releases relay 2103. At the end of the second impulse relays 2101 and 2100 operate causing the release of relays 2105 and 2104. Thus the operation of the relays as described for the first and second impulses are repeated for succeeding impulses. On each operation of relay 2103 a ground connection is established over the odd lead to the six counting relays as shown at the lower portion of Fig. 20, and on the release of relay 2103 an impulse to ground is established over the even lead for these counting relays. The connection for the odd lead is extended through the outer left-hand armature and front contact of relay 2103 through contacts of relay 2102 to ground at relay 2701 and the even lead ground is established over this outer left-hand armature and back contact of relay 2103 to the ground at relay 2701 and relay 2102 releases at the end of each digit to restore the operated relays to normal.

The six counting relays shown at the lower part of Fig. 20 are employed to count the impulses received over the odd or even leads by the operation of the pulsing relay 2101 and serve to transmit the impulses to the storing relays for

the hundreds digits and the tens digits shown in Fig. 15 and to the storing relays for the units digits shown on the upper part of Fig. 20. The fourth or ringing code digits are stored on the counting relays themselves. The counting relays operate as follows: For example, when the first impulse is received over the odd lead relay 2000 is operated from battery through the winding of this relay, contacts of counting relays 2001 and 2002, 2003, 2004 and 2205 to the odd lead to ground on this lead as hereinbefore described as applied to this lead through contacts of relays 2103, 2102 and 2701. Relay 2000 supplies a locking circuit for itself through contacts of relays 2004, 2003, 2002, 2001, 2102 to ground at relay 2701. When ground is supplied over the odd lead and due to the operation of the first counting relay 2000, counting relay 2004 is operated from battery through the winding of this relay, contacts of relays 2000 and 2205 over the even leads through contacts of relays 2103, 2102 to ground at relay 2701. This relay locks over the same circuit that was employed for locking relay 2000 and opens the circuit for this first counting relay which now releases. Relay 2004 prepares a circuit for counting relay 2003 and this relay is operated over the odd lead on the third impulse. Similarly, relay 2002 is operated on the fourth impulse, relay 2001 on the fifth impulse, relay 2006 on the sixth impulse. It should be noted that if relay 2006 operated it locked directly to ground supplied at relay 2701 to contacts of the relay 2102 and remains operated during the succeeding impulses so that on the seventh impulse relays 2006 and 2000 are operated; on the eighth impulse, relays 2006 and 2004; on the ninth impulse, relays 2006 and 2003; and on the zero impulse, relays 2006 and 2002. Thus for the first six impulses one of the six counting relays is operated and for the succeeding four impulses, one of the first five and the sixth relay are operated.

As the counting relays operate and release on the first digit, ground is connected and disconnected from the primary windings of the hundreds register relays 1501 to 1504, for example, the first hundreds digit is usually two impulses. On the first impulse relay 1501 operates from battery through the upper winding of this relay, contacts of relays 1500 and 2000 to ground. When the second relay 2004 is operated, relay 1502 is operated over a circuit from battery, the upper winding of this relay, contacts of relays 1500 to 2004 to ground. If the first digit consists of only two impulses, relay 2102 will release at the end of the digit and operate relay 2107 from battery through the right-hand winding of this relay and its make-before-break contacts, contacts of relay 1500 to ground at relay 2004. Relay 2107 will then close a locking circuit for itself to ground at relay 2701 and a locking circuit for relay 1502 from battery through the lower winding of this relay and its lower upper armature and front contact, contacts of relays 2108, 1500, 2107, contacts of relay 2102 to ground at relay 2701. It will be noted that relay 2203 will also operate at this time from battery through the winding of this relay, contacts of relays 1500, 2107, 2102 to ground at relay 2701. Relay 2203 closes a locking circuit for itself over its own contacts to ground at relay 2202 and provides a substitute locking circuit for relay 1502 from battery and its lower winding and inner lower contact, contacts of relays 2108 and 2203 to ground at relay

2202. Relay 2203 now causes the release of relay 1500 and the operation of relay 1506 from battery through the winding of this relay, contacts of relays 2109, 2203, 2108, 2203, 2202 to ground. Relay 1506 prepares a path for storing the tens digit on the tens relays 1507 to 1510.

When the relay 2102 operates at the beginning of the second digit, it causes the release of relay 2107. If, for example, the tens digit is 1, the counting relay 2000 operates and causes the relay 1507 to operate over a circuit from battery through the lower winding of this relay, contacts of relay 1506 to ground at counting relay 2000. When relay 2102 releases at the end of this second digit, it closes the locking circuit for register relay 1507 from battery through the upper winding of this relay and its upper armature and front contact, contacts of relays 1506, 2107, 2102 to ground at relay 2701. Relay 2109 is now also operated from battery through its winding over the circuit traced for the locking of relay 1507. Relay 2109 opens the circuit for relay 1506 and causes the operation of the relay 2007 from battery, winding of this relay and contacts of relays 2110 and 2109. This prepares a path for the operation of the units storing relays and for the operation of relay 2107 at the beginning of the third digit. That is, when a third digit is dialed and a storing relay, for example, relay 2000 operates, the first unit relay 2008 will operate over a circuit from battery through the upper winding of this relay, contacts of relay 2007 to ground at contacts of relay 2000. This ground on relay 2000 also closes the circuit for the operation of relay 2107 from battery through the right-hand winding of this relay and its right-hand make-before-break contacts, contact of relay 2007 to ground at relay 2000. Relay 2107 closes a locking circuit for itself through its right-hand armature and front contact under control of relays 2109 and relay 2110 to ground at relay 2701. At the end of the digit relay 2102 releases and a locking circuit is provided for the units relay 2008 from battery through the lower winding of this relay and the lower armature and front contact, contacts of relays 2109, 2007, 2107, 2102 to ground at relay 2701. It should be noted that this circuit also operates relay 2110 which locks over a circuit from battery through the winding of this relay and its inner right-hand armature and front contact to ground at contacts of relay 2109. Relay 2109 is locked over contacts of relays 2109, 2203, 2108, 2203 to ground at relay 2202. Relay 2110 in operating opens the circuit for relay 2007 which releases as well as one locking circuit for relay 2107, which is now controlled merely by relay 2102. When the relay 2102 operates at the beginning of the fourth digit, relay 2107 releases. Now when the fourth digit is transmitted through the counting relays these relays are operated to store the fourth digit. At the end of this digit when relay 2102 releases, the counting relay operated will lock. For example, if relay 2004 is operated, it will lock from battery through the winding of this relay and its lower armature and front contact, contacts of relays 2203, 2002, 2001, 2107, 2110, to ground at relay 2701. Thus four digits may be stored on the three sets of register relays and the counting relays as described.

The release of relay 2102 at this time now closes a circuit for the operation of relay 2205 from battery through the winding of this relay, contacts of relays 2110, 2107, 2102 to ground at relay 2701. The circuits are now in condition for again seizing the marker so that a connection

may be completed to the called line in accordance with the setting of the recorder. Relay 2205 in operating closes a circuit for the operation of relay 1000 from battery through the winding of this relay, contacts of relays 2205, 2302, 2301 to ground at key 2200 and this relay in turn operates relays 1100 and 1200 to connect a number of leads as required in establishing the connection to the called line. Relay 2205 also closes a circuit for the operation of relay 1504 from battery through the winding of this relay, contacts of relays 1503, 1200, 2205, 2706, 2303, 2301 to ground at key 2200. This relay operates relay 1602 from battery, winding of this relay, relay 1700 and 1601 to ground. Relay 1602 closes a circuit for the operation of relay 1006 from battery to the winding of this relay, contact of relay 1100, 1604, 1702, 1601 and 1602 to ground. It also operates relay 1810 from battery, winding of this relay, relays 1814, 1610, 1601, 1701 and 1602 to ground. Relay 1810 closes a circuit for the operation of relay 1703 over an obvious circuit. Relay 1703 operates relay 1704 from battery through the winding of this relay, contacts of relays 1703, 1601, 1602 to ground. Relays 1703 and 1006 now operate the recorder-selecting relay associated with this particular recorder circuit, in this case relay 1802 of the group 1802 to 1803. The circuit for this relay is as follows: 30 battery, winding of relay 2300, key 2200, contacts of relays 2205, 2196, 2302, 2301, 1006, 1100, 1804, winding of 1802, contacts of relays 1604, 1702, 1703, 1802 to ground. This causes the operation of relay 1804 from ground through the winding of this relay, contacts of relay 1802, through the circuit traced through the winding of relay 2300 which now also operates. Relay 2300 closes a circuit for the operation of relay 2303 from battery through the winding of this relay, contacts of relays 2300, 1200, 1601 and 1602 to ground. Relay 2303 closes an obvious circuit for the operation of relay 2304. Relay 2304 connects a number of leads required for terminating the call to the called subscriber in accordance with the setting of the recorder. The first effect will be that an idle junctor circuit such as, for example, the one shown at the upper part of Fig. 2 and marked J₂ will be seized. It is evident that a junctor group must first be selected that has access to the hundred lines in which the called line is located, hence the hundreds relay as determined by the dialing of the hundreds digit will operate to choose that particular group of junctors. The hundreds digit has been assumed to be 2 and therefore the hundreds relay 606 will be operated, which will bring the subsequent test and selection to be made in the group of junctors having access to the hundreds group in which the called line is located. It will be remembered that the first digit must consist of at least two impulses. The hundreds relay 606 will therefore now operate from battery through the winding of this relay, contacts of relays 1100, 2304, contacts of the hundreds register relays 1504, 1502, 1501, 2700, 2702, 2205 to ground at relay 2302. A test will then be made for the junctors having access to the tens group in which the called line is located. To this end, the relay 500 will operate to connect a number of leads for this test as this relay is associated with the group of junctors which has been selected as serving the tens group on which the called line may be found. The circuit for relay 500 extends from battery through the winding of this relay, contacts of relays 606, 2304, 1509, 1510, 1508 and

1507 to ground if it is considered that the called line is in the first group of ten in the first hundred. It should be remembered that the tens digit dialed was 1.

Relay 1604 also operates at this time from battery through the winding of this relay, contacts of relays 1100, 606, 2304, 2206 to ground at relay 2709. The operation of this relay causes the release of relays 1802, 1804 and 1036 as these relays are no longer required. As now the junctor group having access to the tens group in which the called line may be found is identified, the relay 501 is operated to prepare the circuit for connecting an idle junctor through the secondary switch SS to the link used by the calling line, that is, by means of the operation of this relay, any line link used may be connected through the secondary switch SS to an idle junctor in the group selected. To start the actual selection of an idle junctor at this time on the operation of relays 500 and 1604, relay 1008 will now be operated over a circuit from battery through the winding of this relay, contacts of relays 1100 and 1604 to ground and relay 902 is also operated which is associated with the ten line links, one of which is associated with a calling line. A circuit for this relay at this time will extend from battery through the winding of relay 902, contact of relay 1100, contacts of the holding magnet 904, contact of relays 2304, 1208 and 1604 to ground. This causes the operation of relay 900 from battery through the winding of this relay, contacts of relays 902, 1100, 1608, 1100 and 902 to ground. This will in turn close a circuit for the operation of relay 407. There is, of course, one of these relays such as 407 provided for each link group per junctor group, that is, this particular relay 407 is associated with the group of junctors that has been selected for the termination of the called line. The circuit for relay 407 extends from battery through the winding of this relay, contacts of relay 501 to ground at relay 900. The specific purpose of this relay will become apparent as the description proceeds. As was stated, relay 1008 was operated to start the selection of an idle junctor. To this end, the operation of this relay and relay 501 will now close a connection to the test relays 1305 to 1306 which will test for an idle junctor. The idle junctors are arranged to test battery through the winding of a relay 200 in the junctors and all of the test relays associated with the idle junctors will operate while those associated with busy junctors will not operate. As the junctor J₂ is considered idle a circuit for relay 1305 may be traced from battery, winding of relay 200, contact of relays 201, 202, 203, 501, 1008, 1100, 1307, winding of relay 1305 to ground at relay 1602. Relay 200 does not operate at this time but relay 1305 operates relay 1307 from ground, winding of this relay, the right-hand make-before-break contacts of relay 1305 to battery at relay 200. This causes the operation of the relay 1310 from battery through the winding of this relay, contacts of relays 1604, 1810 and 1307 to ground and the lower resistance ground connected through the winding of relay 1307 will now operate relay 209 in the selected junctor J₂ which closes various leads with this junctor and the marker circuits. Relay 1310 in operating causes the selection of the called line by the operation of a relay in the group 1301, 1302 and 1303 as controlled by the units digit. If the units digit 9 has recorded, relay 1303 will operate over a circuit as follows: from battery, winding of relay 75

1303, contacts of relays 1310, 1200, 2304, 2010, 2011, 2008 to ground. Relay 1701 will now operate from battery through the winding of this relay, contacts of relay 1303, to the ground hereinbefore traced at contacts of relays 2008 and back to ground at contacts of relay 1602. Relay 1810 will now release, causing the release of relay 1310, which causes the operation of relay 1311, from battery, winding of relay 1311, contacts of relays 1310, 1601, 1810, 1701 to ground at relay 1602. This relay closes leads for testing whether or not the called line is idle or busy. If the line is idle, the holding magnet in the terminating switch in which the called line is located is not operated. As it is assumed that the called line is the one connected to subscriber's station B, the magnet 102 is not operated. Consequently, a circuit will be completed through a make-before-break contact of this magnet 102 for the operation of relay 1812 over a circuit from battery, winding of relay 1812, contacts of relays 1311, 1703, 1800, 1701, 1303, 1100, 500, make-before-break contacts of the holding magnet 102, contacts of relays 500, 1100, 1311, 1303, 1703 to ground. The operation of relay 1812 now begins the selection of the ringing code. Relay 1812 closes a circuit for this purpose to operate relay 1010 over a circuit from battery through the winding of this relay, contact of relays 1100 and 1812 to ground. Relay 1010 now operates the relays in the group 1802 to 1803 for all idle ringing and coin control circuits, the idle ringing and coin control circuits being identified by relays such as relay 800 in the ringing and coin control circuit shown in Figs. 3, 7 and 8 being in non-operated condition. If it is considered that the ringing and coin control circuit shown is idle, a circuit will now be completed for the operation of relay 1802. This circuit will extend from battery through the winding of relay 801 in this ringing and coin control circuit, contacts of relays 800, 802, 803, 1810, 1100, 1804, winding of relay 1802, contacts of relays 1604, 1702, 1703, 1602 to ground, but relay 801 does not operate in this circuit due to the resistance of relay 1802. However, relay 1804 operates over a circuit from ground through the winding of this relay and contacts of relay 1802 to battery, at the left-hand armature and front contacts of this relay. Relay 1804 operating closes a circuit for the operation of relay 801 from ground, contact of relay 1602, resistance 1706, contacts of relays 1804, 1802, 1100, 1010, 803, 802, 800, and winding of relay 801 to battery. This relay 801 starts the connecting up of the ringing and coin control circuit with the marker for the selection of the ringing code as will be hereinafter described. Relay 1804 also operates relay 1012 from battery through the winding of this relay, contacts of relays 1100, 1804, 1810, 1604, 1307 to ground. This relay now further prepares a connection from the ringing and coin control circuit through the connector RC to the junctor J₂, and for the junctor through the secondary switch SS to the selected link and from the junctor to the called line. In the meantime the operation of relay 801 closes an obvious circuit for the operation of relay 805 and this relay closes a circuit for the operation of relay 800 to make this ringing and coin control circuit busy. The circuits are now ready for the setting up of the above-mentioned connections and to apply the code ringing. The immediate result will be the operation of the select magnet in the connector RC for choosing the selected junctor circuit.

This circuit may be traced from battery through the winding of the select magnet 503, contacts of relays 200 and 1012 to ground. The operation of relay 1012 also closes a circuit for the operation of relay 1606 from battery, winding of this relay, contacts of relays 1100 and 1012 to ground whereas the select magnet 503 in operating closes a circuit for the operation of relay 1612 from battery, winding of this relay, contacts of relay 1100 to ground at magnet 503. The effect of the operation of relay 1612 is that the hold magnet 504 is operated in the connector RC over a circuit from battery, winding of magnet 504, contacts of relays 501, 805 and 1209, 1612 and 1604 to ground. The operation of the ringing and coin control circuit will be described hereinafter. It is sufficient to note at this time that the junctor J₂ is connected at the cross-point 506 of the connector RC to the ringing and coin control circuit. As the further effect of the operation of relay 1012, the select magnet 410 in the secondary switch SS is operated over a circuit from battery, winding of this magnet, contacts of relays 200 and 1012 to ground. The select magnet 103 in the terminating switch T₂ is now also operated from battery, winding of this magnet, contacts of relays 200 and 1012 to ground. Now as a result of the operation of the holding magnet 504 of the ringing connector RC, the holding magnet 411 of the secondary switch is operated to connect the link L₁ to the junctor J₂ through the cross-connecting point at 412. The circuit for this magnet may be traced from battery, the winding of holding magnet 411, contacts of relay 407, the cross-connecting point 906 of the recorder connector R/T, contacts of relays 2304, 1200, 1604, 1200, 805 to ground at magnet 504 of the ringing connector, thus the calling line is now connected to the link of 402 at the cross-connecting point 405 of the originating line connecting switch and at the point 412 of the secondary switch to the junctor shown in the upper part of Fig. 2. The hold magnet 102 in the terminating switch T₂ will now be operated in the same manner as was the corresponding magnet 101 of the terminating switch T₁ which, as noted, was operated on the operation of the holding magnet in the call originating switch CO. In this case, therefore, it was assumed that the called line was the tenth line in the same group of lines as the calling line and consequently the line identifying relay 1303 is operated as hereinbefore described. It follows, therefore, that on the operation of relay 1606 the corresponding holding magnet 414 is operated over a circuit from battery through the winding of this magnet, windings of relays 500, 1100, 1311, 1303 and 1606 to ground. Magnet 414 in operating operates magnet 102 on an obvious circuit. Thus the called line B is now connected at the cross-connecting point 105 to the junctor J₂ and connection between the subscribers A and B is therefore now completed. The setting up of the code for ringing in the ringing and coin control circuit, which was started on the operation of relay 801, has proceeded in the meantime and after this is set up the called subscriber may be rung.

These operations to select the calls will now be described. When relay 801 is operated and the ringing and coin control circuit is connected to the marker, if the code digit dialed was 1, the register relay 2000 would be operated. This causes the operation of relay 700 in the ringing and coin control circuit from battery through the winding of this relay, contacts of relays 801,

2304 and 2000 to ground. Other codes may be selected by the operation of other register relays as operated by the fourth digit to operate relays in the ringing and coin control circuit in various combinations such as relays 700, 101, 102 and 703. Relay 700 closes a circuit for relay 807 from battery through the winding of this relay, contacts of relays 805 and 700 to the above-mentioned ground for the operation of relay 700, and contacts of relay 2000. Relay 807 prepares a locking circuit for relay 700 and operates relay 802 over an obvious circuit. Relay 704 now also operates from battery through the winding of this relay, contacts of relays 700 and 800 to ground, that is, this relay 704 operates due to the operation of relay 700 to prepare the circuit for transmission of the code. The relay 807 partly closes a circuit for a pick-up relay 704 which will be operated presently. Returning now to the circuit closed by the connection of the calling line to the junctor J₂, this causes the operation of the relay 204 over the tip and ring conductors of junctor J₂, contacts of relays 203, the connection at cross-connecting point 412, a link L₁, cross-connecting point 405 and the calling subscriber's loop at A. Relay 204 closes an obvious circuit for the operation of relay 202. Relay 202 in operating closes a circuit for the release relay 1700 from battery through the winding of this relay, contacts of relays 1100, 200 and 202 to ground. This begins the release of the marker and the recorder and permits the starting of the transmission of the ringing code. The first effect of the operation of relay 1700 is the release of relay 1812. Relay 1812 releases relays 1703 and 1602. Relay 1602 releases relay 2303 which releases relay 2304 and the recorder is now released by the release of holding magnet 904. The marker is also released by the release of relays 1601, 500, 606, 1604, 501, 1008, 902, 900, 407, 1000 and 1100. Relay 1602 also releases the other relays in the marker such as 1704, 1311, 1309, 1301, 1305, 1803, 1804, 1305, 1307 and 1012, 1606, also the relay 200 in the junctor J₂ and the release magnet 1700 and relay 1602 as well as the select magnets 403, 410 and 503 of the connector RC, secondary switch SS and the terminating switch T₂. Returning now to the release of relay 1602, this relay also releases relay 1010 which in turn causes the release of relays 801 and 805 in the ringing and coin control circuit. The release of relay 805 causes the called subscriber to be rung in the following manner. When ground is supplied from the power circuit as shown in Fig. 3, relay 705 operates over a circuit from battery, winding of this relay and its left-hand make-before-break contacts of relays 810, 807, 805, the pick-up commutator cam 303, the power circuit shaft to ground. The release of relay 805 also connects the relay 811 from battery and ground through its windings over the tip and ring conductors to the called line through contacts of relay 805, the connection at contacts of relays 707, 708, 709, cross-connecting point 506 of the ring and coin control connector, switch RC, contacts of relay 201 and the cross-connecting point 105 through the subscriber at B. Relay 705, as soon as it operates, closes a circuit for the operation of relay 710 in accordance with the code as determined by the relay 700, that is, relay 710 will operate once for each revolution of the power ringing circuit shaft which controls cam 304. The circuit for relay 710 may be traced from battery through the right-hand winding of this relay, contacts of relays 712, 705, 700, 701,

703, 702, cam 304 to ground. Relay 710 in operating closes a circuit for the operation of relays 709 which disconnects the relay 811 from the line and the ringing code is now connected to the line over the contacts of relay 709 as follows: Generator 381 will induce alternating current signals through the repeating coil 395 through contacts of relays 703, 704, 710, 709, over the ring conductor to the called subscriber's line. It may be assumed that with this code party No. 1 connected on the ringing side of the line as subscriber B will be rung by this signal. The arrangement in the ringing and coin control circuit and power circuit is such that ringing codes may be provided for twenty parties, ten parties for each conductor and each party receiving different codes. The ring side will receive odd codes and the tip side will receive even codes. It should be noted that on the operation of relay 709 a circuit is closed for the operation of relay 708 which prepared a ground and battery connection through a resistance for the line. Thus, when relay 710 releases, ground is connected to the ring conductor momentarily through the left-hand make-before-break contacts of relay 710 and contacts of relay 712. This momentarily shorts-circuits the line until relay 709 releases to reduce the level of the kick in case the subscriber answers during the ringing interval and when relay 709 releases due to the release of relay 710 and before the slow-release relay 708 releases, the line is momentarily connected to ground and through resistance to battery at the front contacts of relay 708, thus discharging the line. When relay 709 releases, the line conductors are connected to the ringing trip relay 811. Ringing is thus continued until the subscriber answers. When the subscriber answers the relay 811 is operated, causing the release of relay 807 which causes the release of relay 700 and relay 708 now disconnects the ringing circuit from the junctor by operation of the relay 201 in the junctor circuit J₂ from battery, lower winding of relay 201, contacts of relay 203, the cross-connecting point 506, contacts of relays 707, 810, 814, 802 and 805 to ground. The operation of relay 201 disconnects the called line from the ringing circuit causing the release of relay 810. This causes the release of relays 802, 800 and the holding magnet 504 which releases the ringing circuit from the junctor by the release of the ringing connector switch RC. Relay 201 locks through a ground at relay 202 and the called subscriber will now be connected for talking battery through the contacts of relay 202. The calling subscriber receives his talking battery through the winding of relay 204 and conversation may now take place through the condensers 206 and 207.

If the calling subscriber releases first at the end of the conversation, relays 204 and 202 release which opens the holding circuit for the holding magnet 400 at the contacts of relay 202 that extended over the cross-point 405 in the call originating switch CO over the sleeve and the cross-connecting point 412 in the secondary switch SS through contacts of relay 202. Relay 202 now also in releasing opens the circuit for the holding magnet 414 of the call terminating switch T₂ but as the called subscriber has not replaced his receiver on the switchhook, the line relay 110 will therefore now operate and close a holding circuit for the holding magnet 102 from battery through the winding of this magnet and its upper armature and front contact to ground at contacts of relay 110. Relay 110 now also op-

erates relay 203 over a circuit from battery through the upper winding of this relay, contacts of relays 200, 202, cross-connecting point 105 to ground at the upper armature and front contact of relay 110. Relay 203 holds relay 201 operated over the lower inner armature and front contact of relay 201, contacts of relay 203 to ground. This holds the junctor busy and the operated condition of holding magnet 102 prevents the called line from initiating another call at the ground connection at the lower armature and front contact of the line relay 110 is not extended at the make-before-break contacts of this holding magnet. Then when the called subscriber releases, relay 110 releases, causing the release of relays 203 and 201 and the holding magnet 102 and thus freeing the junctor end. All the circuits are now returned to normal condition ready for another call.

In case the line to which station A is connected had also been connected to other subscribers' stations, that is, in case this line is a party line and the subscriber A had called another party on this line, the operations for establishing a connection to such other party would be the same as in the case hereinbefore described where the subscriber B was called up to the point where the test for the called line begins. When this test is begun, the called line would, of course, be busy as the calling subscriber A will be connected to this line. Therefore, at this time when relay 1310 is released and relay 1311 operates, relay 1812 would not operate as the holding magnet 101 of the calling line is operated when relay 1311 operates to perform this test. Hence, the procedure to establish a connection will not continue in the same manner as described beginning with the operation of relay 1010, but instead relay 1703 will release on the release of relay 1810 and consequently on the release of this relay 1703, relay 1707 will operate over a circuit from battery, winding of relay 1707, contacts of relay 1703, the operated identifying relay in the groups 1301 to 1303, contacts of relays 1311, 1100, 500, magnet 101 of the terminating switch to ground at magnet 400 of the originating switch. This relay 1707 closes a circuit for relay 1708 from battery, winding of relay 1708. Relay 1708 in turn operates relay 1709 over a circuit from battery, winding of relay 1708 and its contacts, left winding of relay 1709, contacts of relay 1700 to ground in the sleeve lead through the holding circuit for the hold magnet 400 as described. At this time, however, relay 1010 operates over a circuit from battery, winding of this relay and contacts of relays 1100 and 1709 to ground and this relay 1010 operates relay 1802 as described to select an idle ringing circuit and this relay in turn operates relay 1804 as described to operate relay 1012 as described. It will now be noted that the select magnets 503 and 410 for the ringing connector and the secondary switch, respectively, are operated, and that a select magnet such as 115 of the terminating switch is operated. The select magnet 115 is, of course, associated with the terminating switch in which the calling line is to be found and is operated for the purpose of selecting the outgoing end of a junctor which, however, in this case is not connected up as the holding magnet 101 is already operated. The select magnet 503 now operates the holding magnet 504 in the ringing connector and this magnet in turn operates relay 1612. The above-mentioned relay 1606 also in operating causes the operation of relay 2301 to operate the holding magnet 511

in the secondary switch but holding magnet 400 will, of course, not be affected by the operation of relay 1606, as it has already been operated to connect the calling line to the originating switch by the operation of relays 1707 and 1708. As the ringing circuit has already been selected and connected in the usual manner at this time and the connection between the junctor selected and the calling line is established, relay 202 in this junctor is now operated. This operates relay 204 which in turn operates relay 1700 which releases relay 1602 and this relay causes, as described, the ringing of the called subscriber on the party line and in turn disconnects the ringing circuit from the marker, disconnects the junctor from the marker and disconnects the recorder from the marker so that the marker now returns to common use all in accordance with the descriptions already made in connection with the regular call. Relay 202 now also causes the operation of relay 203 which causes the release of relay 202.

When the called subscriber answers the ringing trip relay 811 operates causing the release of relay 867 as described, which in turn starts the release of the ringing circuit from the junctor, as described, and also the release of relay 204. Relay 204 opens the holding circuit for the holding magnet 400 which releases the line from the line link and this causes the release of the holding magnet 411 in the secondary switch which releases the connection to the junctor and the relays operated in the connection established through the junctor are all released as hereinbefore described. The magnet 400 in releasing opens the circuit for the holding magnet 101 and also connects the calling subscriber's line to the line relay 100 which operates and as the holding magnet 101 is slow in releasing, it is now held by the line relay. Talking battery is furnished through the windings of the line relay 100 and conversation between the calling subscriber over the party line may now take place. When either of the subscribers replaces his receiver, the line relay releases, which in turn causes the release of the holding magnet 101.

In case the station of the calling subscriber A had been a coin station, the connection to the called subscriber B would not be completed without the calling subscriber A first depositing a coin. The arrangement would be such that when the calling subscriber hears a coin tone, it indicates to him that the called subscriber has answered the call and that he should deposit a coin, and a description of the operation of the circuits in this case will now be made. It will be noted that in this case the group relay 500 would have a ground connected at one of its contacts which would start the operation of the circuits for this purpose. It might be mentioned that the coin line subscribers may be segregated so as to be identified by the operation of relay 500 while other subscribers' lines would be segregated and identified by the operation of other group relays. Therefore when relay 500 operates and after relay 1001 is operated, a certain relay 2305 will operate over the circuit from battery, winding of relay 2305, contact of relays 1001 and 500 to ground. Relay 2305 closes a circuit for operation of relay 803 from battery, winding of this relay, contacts of relays 2304 and 2305 to ground. It is evident, however, that the actual testing for a deposited coin does not start until the subscriber B has answered and the ringing tripping operations have taken place as hereinbefore described. At this time, when relay 802 releases as described,

ringing and coin connector RC is not immediately released but instead the relay 707 operates over a circuit from battery, winding of this relay, contacts of relays 803, 813, 862, 805 and 809 to ground. Relay 707 now locks over a circuit from battery, winding of relay 707 and contacts of relay 800 to ground. This relay 707 now disconnects relay 811 from the tip and ring conductors and connects the tip conductor to ground through the winding of relay 714 and the ring conductor to battery through the winding of relay 715. The junctor circuit employed is now split by the operation of relay 203, to separate the calling line from the called line, over a circuit from battery, lower winding of relay 203, contacts at cross-point 503 of the ringing and coin connector RC, contacts of relays 813, 707, 815 and 805 to ground. Relay 204 now releases on the operation of relay 203 but relay 202 which is slow in releasing is held by the operation of relay 203 over a circuit from battery, winding of relay 202, contacts at cross-point 506, contacts of relays 513, 707, 803, 815 and 805 to ground. Relay 202 by remaining operated prevents the release of the connection through the ringing and coin connector. Relay 203 in operating now connects the tip and ring conductors from the calling line to ground through the winding of relay 714 and to battery through the winding of relay 715 and these two relays are thereby operated over the circuit through the calling subscriber's loop. These relays close a circuit for the operation of relay 816 from battery, winding of this relay, contacts of relays 715, 714 and 800 to ground. Relay 707 also connects at its contacts the ring conductor to the tone source 390. Coin tone will now be heard by the calling subscriber which indicates that the called subscriber has answered and that the coin should be deposited. When the calling subscriber deposits the coin, it is well known in the art that the subscriber's circuit may be arranged to momentarily introduce a high resistance across the line conductors by the coin. This high resistance causes the marginal relay 715 to be momentarily released while relay 714 remains operated. This closes a circuit for the operation of relay 815 from battery, winding of this relay, contacts of relays 707, 816, 715, 714, and 800 to ground. Relay 815 locks over a circuit from battery, winding of relay 815, contacts of relays 707, 815 and 800 to ground and releases relay 803 which in turn releases relays 800 and 707 and relay 707 releases relay 815. Relay 800 releases the holding magnet 504 which releases the ringing and coin connections RC. Relay 815 releases relay 203 which now holds relay 202 operated and also releases relays 714 and 715 which release relay 816 and the talking connection between the calling subscriber's line and the called line is now completed.

A description will now be made of a call from one subscriber's line to a distant office over an idle trunk in a group of trunks leading to this office. One trunk has been shown in detail in Figs. 14 and 19 terminating in the recorder and trunk connecting switch RT and accessible through either of the two by-links shown in Figs. 24, 25 and 26. In order to establish such a connection, a calling subscriber must dial a trunk code digit and the operations of the circuits are as follows: When the subscriber calls, a connection is established in the same manner as hereinbefore described for a subscriber-to-subscriber call up to and including the dialing of the first digit, that is, an idle recorder and an idle link

are chosen and the recorder is connected through the link to the calling line and the subscriber dials the trunk code which is registered as the first digit in the recorder. When this digit has been dialed, the relay 2102 will release as described. This causes the operation of the relay 2203 over a circuit as mentioned and the hundreds storing relay or relays that have been operated are locked. Relay 2203 releases relay 1500. If now, for example, the hundreds digit 7 has been dialed an idle trunk is selected in the trunk group leading to the desired distant office. In this trunk group the trunk shown in Figs. 14 and 19 has been shown. To start the establishing of a connection through this trunk, relay 2706 will now operate over a circuit from battery through the winding of this relay, contacts of relays 2302, 2702 and 1512, contacts of storing relays 1501, 1502, 1503 and 1504 and the contacts of relays 2203 and 2701 to ground. It should be noted that relay 1512 was operated on the operation of relay 1606 as hereinbefore described in connection with a line-to-line call. Relay 2706 in operating closes a circuit for the operation of relays 2205 from battery through the winding of this relay, contacts of relays 2706 and 2701 to ground. Two by-link circuits have been provided, by-link 1 shown above the dash-dot line and by-link 2 below this line running across the Figs. 24, 25 and 26. Arrangements are made so that normally relays 2604 and 2605 of the two by-links are in operated position. This may be done by momentary impulses to ground over the leads BL₁ and BL₂ in any suitable manner. Relay 2604 causes the operation of relay 2607 over a connection from battery, winding of this relay, contacts of relays 2606 and 2604 to ground. Relay 2607 closes an obvious circuit for operating relay 2603. These relays 2603 and 2607 now remain operated. Relay 2605 is locked over contacts of relay 2603 and relay 2604 is locked over contacts of relays 2610, 2600, 2601 and 2611 to ground. If this condition of the relays mentioned prevails, by-link 2 will be first seized by a call to a distant office. If this by-link is taken for use, relay 2606 will operate as will hereinafter be described causing the release of relays 2607, 2603 and 2605 and the next call for a trunk will be established over by-link 1. Then the relay 2604 will be released and relay 2605 will operate which releases relay 2606 and causes the operation of relays 2607 and 2603 and then the next call coming in will choose by-link 1, thus by the alternate operation and release of the relays mentioned alternate by-links are employed by succeeding calls through trunks. If it is assumed that by-link 1 will be chosen at this time the operation of relay 2706 now therefore causes the operation of relay 2609 from battery through the winding of this relay, contacts of relays 2610, 2603, 2706 to ground at relay 2702. Relay 2600 opens the circuit for relay 2610 which is employed when calls are incoming over trunks as will hereinafter be described and relay 2604 is now released as the locking circuit for this relay is opened at the contacts of relay 2600. In each link there is the group of relays for selection of the seized recorder; the first and the last of these for link 1 have been shown numbered 2400 and 2401. One of these relays is assigned to each recorder and will operate depending on which recorder is used in a call. If as in this case, the first recorder is used, relay 2400 will operate over the circuit from battery, winding of relay 2400, windings of relays 2500, 2706, 2600, 2612, 2603 to ground. Relay 2400 provides a locking circuit for

itself through its upper middle armature and front contact through contacts of relays 2612 and 2600 to ground and closes an obvious circuit for the operation of relay 2500. Relay 2500 opens the energizing circuits for all of the recorder relays 2400 to 2401. There is also a group of relays in each by-link such as at 2402 and 2403 which are provided for selecting an idle trunk in a selected group of trunks. Relay 2402 is provided for the first trunk and relay 2403 for the last in any group. As digit 7 was dialed and this represents the first group of trunks, a corresponding group relay 2501 will now operate to connect lead for testing for an idle trunk and the circuit for this relay extends from battery, winding of this relay, contacts of relays 1502, 1504, 1501, 2400, 2603 to ground. Now the idle trunks in the selected group have batteries so connected that all relays such as 2402 to 2403 of idle trunks will operate. If the first trunk is idle, a connection will be established for the operation of relay 2402 as follows: From battery, key 1408 contacts of relay 1900 in the first trunk, winding of relay 2402, contacts of relays 2405, 2406, 1901, 2501, 2612, 2603 to ground. The operation of this relay 2402 or any of the relays for the trunk will now operate relay 2408 over an obvious circuit. Relay 2402 is locked over its lower inner armature and front contact, contacts of relay 2612 to ground at relay 2600, while relay 2406 causes the release of all the other relays, such as 2403 of other idle trunks in the group. As now the trunk shown in Figs. 14 and 19 has been chosen, relay 1400 therein operates over a circuit from battery, winding of relay 1400, contacts of relays 1903, lower left-hand winding of induction coil 1401, contacts of relays 1402, 2402, 2400 and 2706 to ground. Relay 1400 in operating closes an obvious circuit for the operation of relay 1403. Relay 1404 also operates on the operation of relay 2402 over a circuit from battery, winding of relay 1404, contacts of relays 1903, 1901, 1900, 2402, 2500 to ground. This closes a circuit for relay 1405 from battery, winding of this relay, contacts of relays 1404 and 1400 to ground. Relay 1405 closes an obvious circuit for the operation of relay 1905 and this relay in turn operates relay 2702 from battery, winding of relay 2702, contacts of relays 2701, 2703, 2400, 2502, 2402, 1900, 1905 and 1900 to ground. It should be noted also that relay 1905 closes a circuit for the operation of relays 2612 from battery, winding of this relay, contacts of relays 2401, 2412, 2500, 2402, 1900, 1905 and 1900 to ground. This relay in turn causes the operation of relay 2606 from battery, winding of this relay, contacts of relays 2605, 2606, 2615 and 2612 to ground; thus this relay causes the release of relays 2607, 2603 and 2605 to prepare by-link 2 for reception of the next call. Now the operation of relay 2702 causes the release of relay 2706 so as to cause the seizure of the marker circuit and relay 2600 is also released due to the operation of relay 2702, relay 2600 in turn releasing the trunk group relay 2501. The seizure of the marker is now accomplished by the operation of relay 1000 over a circuit from battery, winding of this relay, contacts of relays 2205, 2706, 2303, 2301 and ground at key 2200. This relay in turn operates relays 1100 and 1200 over obvious circuits. Relay 1601 is now operated over a circuit from battery, winding of this relay, contacts of relays 1600, 1200, 2205, 2706, 2303, 2301, and key 2200 to ground and this relay in turn causes the operation of relay 1602 from battery, winding of this relay, contacts of relays

1700 and 1601 to ground. Relay 1602 causes the operation of relay 1006 from battery over the winding of this relay, contacts of relays 1100, 1604, 1702, 1601 and 1602 to ground. Relay 1602 also operates relay 1810 from battery through the winding of this relay, contacts of relays 1814, 1610, 1601, 1701 to ground at relay 1602. Relay 1810 operates relay 1703 from battery through the winding of this relay, contact of relay 1810 to ground. Relay 1703 now operates one of the marking relays 1802 to 1803, and as the trunk selected is in the first group, relay 1802 operates over a connection from battery, winding of relay 2300, key 2200, contacts of relays 2205, 2705, 2302, 2301, 1036, 1100, 1804, 1802, 1604, 1702, 1703, 1602 to ground. Relay 2300 does not operate in this circuit but on the operation of relay 1804 as hereinbefore described, relay 2300 will operate over the same circuit as relay 1802 was operated up to the contacts of relay 1100 and from there through contacts of relays 1802, 1804, resistance 1706 to ground at contacts 1602. Relay 2300 operates relay 2303 and this relay in turn operates relay 2304 over circuits as hereinbefore described. The operation of relay 2304 causes the operation of relay 1907 from battery, winding of relay 1907, contacts of relays 2402, 2502, 2400, 2704, and 2304, 2700 to ground. As a result of the operation of relay 2304, relay 610 is operated over a circuit from battery, winding of this relay, contacts of relays 1100, 2304, 1502, 1504, 1501, 2400, 2600 to ground. This relay operates relay 1806 from battery, winding of this relay, contacts of relays 1100, 610, 1100, 1610, 1608, 1601 and 1602 to ground and relay 1806 closes an obvious circuit for relay 1636, which in turn operates relay 2301 over a circuit from battery, winding of this relay, contacts of relays 2302, 2304, 1200, 1610, 1606 and 1700 to ground. Relay 2301 releases relay 2101. Relay 1806 also operates relay 1814 over an obvious circuit and this relay causes the release of relay 1810 and operates relay 1702 over an obvious circuit which causes the release of relays 1006, 1802 and 1804. Relay 1810 releases relay 1703, whereas relay 1814 now operates a select magnet 901 of the recorder and trunk switch RT and also the select magnet 403 of the call originating switch CO; the circuit for the select magnets 901 and 403 extends from battery through the winding of these magnets and contacts at the cross-point 906, which was established when the recorder was connected to the link L₁ on the seizure of the recorder by the calling line, contacts of relay 2304 to ground at relay 1814. The select magnet 403 in the call originating switch CO closes a connection for the operation of relay 902 from battery through the winding of this relay, contacts of relay 1100 to ground at select magnet 403 and this relay in turn operates relay 900 from battery through the winding of this relay, contacts of relays 1100, 1600 and 902 to ground. The holding magnet 910 in the switch RT now operates to connect the chosen trunk to the link L₁ which is connected to the call originating line switch CO to the calling line. Magnet 910 will operate over a circuit from battery through the winding of this magnet, contacts of relays 900, 1907, 1200, 1702, 1200, 2304, 1100, 1606, 1814, 1601 and 1602 to ground. This closes a connection at the cross-point 912 between the trunk shown in Figs. 14 and 19 and the link L₁ which is also connected at the cross-point 405 to the calling subscriber. Relay 1900 now operates over a circuit from battery winding of 75

this relay, contacts of relays 1907, 1806, 1200, 1907, 1905, 1003, 910 to ground. This causes the operation of the release relay 1700 from battery through the winding of this relay, contacts of relays 1610, 1200, 1907, 1900 to ground. As the connection is now established from the calling subscriber to the trunk, the recorder and marker may be returned to normal position. Consequently relays in these circuits are released as well as the select magnets 901 and 403. The only relays remaining operated in the trunks are relays 1400, 1404, 1405, 1900, 1905 and 1907. The by-link relays are, of course, also released, such as 2400 and 2402. It should be noted, therefore, that on a call from the calling line A to the trunk shown in Figs. 14 and 19, as described, a connection is first established from the calling line to the trunk through the by-link 1 and then from the calling line to the trunk through the link L₁. The first connection enables the switches at the distant office, such as a usual line finder to establish a connection to a usual first selector as an immediate result of the calling subscriber dialing the office digits and the calling subscriber may therefore continue to dial succeeding digits over this first connection to establish a connection without waiting for the second connection to be established as this second connection may be delayed in case a marker is not connectably available.

The circuit over which dialing may take place through the by-link is as follows: From the subscriber's loop at A over the tip and ring conductors, contacts at cross-point 495, link L₁, contacts at cross-point 906, contacts of relays 2702, 2400, 2402, 1402, left-hand winding of repeating coil 1401, contacts of relays 1903, windings of pulsing relay 1400 to battery and ground. In case dialing has not been completed by the time the second connection is established, it may continue uninterruptedly over the new connection over contacts at cross-point 912 and over contacts of relay 1402, left-hand windings of repeating coil 1401, contacts of relay 1903 to battery and ground over windings of the pulsing relay 1400. The pulsing out over the trunk is accomplished by a pulse correcting arrangement controlled by pulsing relay 1400 as follows: While relay 1400 releases, the relays 1409 and 1407 start operating in parallel. The relay 1407 is fast in operation and operates before the relay 1409. In fact the relay 1409 may not operate at all if the back contact closures of relay 1400 are short. In this case the outgoing pulsing circuit over the trunk is held open by the relay 1407 until relay 1400 operates and releases it. Under such conditions the outgoing open pulse is equal to the back contact closure time of the relay 1400 plus the release time of the relay 1407, minus the operating time of the relay 1407. In case the back contact closures of the relay 1400 are long enough to cause the relay 1409 to operate, it releases the relay 1408 and stays operated until the relay 1400 reoperates. Under this condition the maximum outgoing open pulse is limited to the operate time of the relay 1409 plus the release time of the relay 1407 minus the operating time of the relay 1407. Thus the pulses outgoing over the trunk to the distant offices are corrected to maintain the proper relation between the open and closed periods of the circuits. When the relay 1407 operated on a first pulse, it operated the relay 1410 which places battery and ground on the tip and ring conductors of the trunk and eliminates the bridge across these conductors.

Relay 1410 remains operated during the pulsing of each digit. When the call is answered from the distant end of the trunk, relay 1408 operates over a circuit from the tip and ring conductors of the trunk, contacts of relay 1407, right-hand windings of repeating coil 1401, contacts of relay 1404, contacts of relay 1405 and across the lower winding of relay 1408. Relay 1408 closes a circuit for the operation of relay 1411 which releases relay 1409. Relay 1409 releases which 10 causes the release of relays 1405, 1905 and opens the trunk loop through the lower winding of relay 1408 but leaves the loop connection through the upper winding of this relay causing relay 1408 to hold relay 1411 operated. Relay 1411 holds ground on the sleeve to maintain the closure through the cross-points. When the called party at the distant end is disconnected, 1408 and 1411 release, releasing the magnets 910 and 400. The release of the hold magnet 910 at the release of relay 1404 returns the trunk to normal condition.

A description will now be made of a call incoming from a trunk to a subscriber in this office. If the trunk shown in Figs. 14 and 19 is calling, relay 1910 will operate over a circuit from battery and ground through the two windings of this relay, contacts of relays 1911 and 1904 and right-hand windings of repeating coil 1481 to the trunk from the distant office. Relay 1910 closes a circuit for the operation of relay 1905 from battery through the winding of this relay, contacts of relay 1910 to ground. The start relay 1901 is also operated from battery through the winding of this relay, contacts of relays 1903 and 1910 to ground. Start relay 1901 immediately seizes a by-link, for example, No. 1, by the operation of relay 2610, from battery through the winding of this relay, contacts of relays 2609, 1801, 2611 and ground at 1901. Relay 2510 closes a circuit for relay 2503 from battery through the winding of this relay, contacts of relays 2610, 2612 and 2603 to ground, and also initiates the selection of an idle recorder and one of the relays 2400, 2401 or intermediate relays representing different recorders is operated. If the first recorder is idle, relay 2400 will operate from battery, winding of relay 2400, contacts of relays 2500, 2503, 2701, key 2200, contacts of relays 2610, 2612, and 2603 to ground. It is evident that any other relay representing other idle recorders will also operate at this time but the relay of the lowest number recorder will lock and the other relays release, relay 2400 locking over its second upper armature and contacts of relays 2612 and 2310 to ground. As the trunk shown in Figs. 14 and 19 is calling one of the relays 2402, 2403 will operate, and if 2402 represents this trunk this relay will operate over a circuit from battery at key 1403, contacts of relay 1900, winding of relay 2402, contacts of relays 2405, 2406, 1901 and 2610, 2612, 2603 to ground and this relay in turn operates relay 2406 over an obvious circuit. The selection of the idle recorder is continued on the operation of relay 2400 by the operation of relay 2500 from battery through the winding of this relay, contacts of relay 2400 to ground. Relay 2500 in operating opens the energizing circuit for the remaining relays, such as 2401. Relay 2500 causes the operation of relay 70 2612 from battery through the winding of this relay 2406, 2612, 2500, 2502 and 2610 to ground. Relay 2612 releases relay 2503 and operates relay 2606 from battery through the winding of this relay, contacts of relays 2605, 2615, 2612 to 75

ground. Relay 2606 releases relays 2607, 2603 and 2605 thus assigning the by-link 2 for the next call. By the operation of relay 2500 relay 1903 was also operated from battery through the winding of this relay, contacts of relays 1901, 1903, 2402 and 2500 to ground. Relay 1903 releases relay 1901 and causes the operation of relay 2101 over a circuit extending from the dial tone source at 300 as hereinbefore traced to the left-hand winding of relay 2101 and from battery through the right-hand winding of this relay to contacts of relays 2300, 2701, 2400, 2402 and 1402, left-hand winding of repeating coils 1401, contacts of relays 1903 and 1910, lower winding of relay 1403, whereby dial tone is submitted over the trunk to indicate that a recorder has been selected and the circuit is ready for receiving the dial pulses. Relay 2101 also prepares the usual circuit as hereinbefore described for the operation of relay 2100 which in turn operates relays 2202 and 2701 as hereinbefore described. The dialing of the desired subscriber's number may now take place by interrupting the circuit for relay 2101 by relay 1910 controlled over the trunk and the recorder set in accordance with the dialed number in the same manner as the setting of this recorder by dial pulses received from the calling subscriber's line.

In the meantime while the dialing takes place it is to be noted that on the operation of relay 2400, the relay 2703 was also operated over a circuit from battery, winding of this relay and contacts of relays 2701, 2400, 2502 and 2612. This causes the operation of the start relay 2700, to seize the marker, over a circuit from battery through the winding of relay 2700, contacts of relay 2703 to ground. Relay 2700 closes a circuit for the operation of relay 2206 and also a circuit for relay 1000 from battery through the winding of this relay, contacts of relays 2700, 2302, 2301, key 2200 to ground. Relay 1000 closes a circuit for relays 1100 and 1200 and relay 1601 is now operated from battery through the winding of this relay, contacts of relays 1600, 1200, 2700, 2302, 2301 to ground at key 2200. This causes the operation of relay 1602 from battery, winding of this relay, contacts of relays 1700 and 1601. Relay 1602 operates relay 1006 from battery through the winding of this relay, contacts of relays 1100, 1604, 1702, 1601 and 1602 to ground and it also operates relay 1810 from battery through the winding of this relay, contacts of relays 1814, 1610, 1601, 1701 and 1602. Relay 1810 operates 1703 over an obvious circuit and relay 1802 now operates to mark the calling trunk as hereinbefore described. Relay 1802 operates relay 1804 and relay 2300 is now operated which in turn operates relay 2303 and this relay operates relay 2304 over circuits as hereinbefore traced. Relay 2304 operates relay 1610 from battery through the winding of this relay, contacts of relays 1200, 2304 and 2700 to ground. Relay 1610 operates relay 1907 from battery through the winding of this relay, contacts of relays 2402, 2502 and 2400, 2704, 2304, 2302, 2301 to ground at key 2200. Relay 1003 is also operated by relay 1610 from battery through the winding of this relay, contacts of relays 1100 and 1610 to ground. In parallel with this relay, relay 1004 is also operated over the same circuit. Relay 1610 causes the release of relay 1810 which in turn releases 1703 and relay 1703 releases relay 1704. Relay 1907 causes the operation of relay 1610 from battery through the winding of this relay, relays 1100 and 1907

to ground. This relay 1610 determines the trunk group in which the calling trunk is located. Relay 1900 is also operated over a circuit from battery through the winding of this relay, contacts of relays 1200, 1907, 1900 and 1903 to ground and the circuits are now ready for the selection of an idle line link such as L₁ for the connection of the seized recorder to this link and to the calling trunk through the recorder and trunk switch TC so that the dialing may proceed if it has not already been completed through this switch TC from the calling trunk and also for the connection of the trunk to the called line as will hereinafter be described. An idle link was selected by the operation of one of the relays 1305 to 1306 and if 1305 is operated the first idle link L₁ is selected. Relay 1305 operates over a circuit from battery, contacts of relay 1004, contacts of relays 900, 1003, 1100, 1305 to ground at 1602. Relay 1305 operates relay 1307 and the select magnet 901 in the recorder and trunk switch and the corresponding select magnet 403 in the call originating switch CO is operated from battery through the windings of these magnets, contacts of relays 900, 1100, 1305, 1814, 1604, 1307 to ground. Relay 902 is now operated from battery through the winding of this relay, contacts of relay 1100 and contacts of magnet 901 to ground. This causes the operation of relay 1606 from battery, winding of this relay, contacts of relays 1610, 1100 and 902. The holding magnets for connecting the idle link L₁ to the recorder and to the calling trunk are now operated. The holding magnet 904 for connecting the recorder is operated over a circuit from battery through the winding of this magnet, contacts of relays 900, 2300 and 1200 and 1606 to ground at 1610 and the holding magnet 910 for connecting the link L₁ is operated from battery through the winding of this magnet, contacts of relays 900, 1907, 1200, 1610 to ground at relay 1608. The holding magnet 910 operates relay 2201 from battery through the winding of this relay, contacts of relays 2202, 2302, 2301 to ground at relay 2101. This causes the operation of relay 1900 from battery, winding of this relay, contacts of relays 1907, 2303, 2703, to ground at contacts of relay 2201. Relay 1900 releases relays 2402, 2407 and 2610 and thus frees the by-link for use by some other call. Relay 1900 also operates the release relay 1700 which in turn releases relay 1602 and the marker is released in the manner as hereinbefore described.

The calling trunk is now connected to the link L₁ to the recorder directly and dialing, if not already finished, may continue through this link. When the dialing is finished in the manner as hereinbefore described, the establishing of a connection to a called subscriber proceeds in the same manner hereinbefore described in connection with a subscriber-to-subscriber call except that in this case the call is from a trunk and hence extends over the switch TC to a link, and from this point on it extends in the same manner over a junctor circuit and a call terminating switch to the called line.

What is claimed is:

1. In a telephone system, calling lines, called lines, linking and switching means, a plurality of ringing circuits, means operated when a call is made from a calling line for establishing a connection from said calling line to a called line over said linking and switching means, means operative when said connection has been estab-

lished for associating an idle ringing circuit with said called line over said linking and switching means and for ringing the called line from said ringing circuit, and means responsive when the subscriber of the called line answers for releasing said ringing circuit.

2. In a telephone system, calling lines, called lines, switching means, link circuits, junctor circuits, register circuits, ringing circuits, a marker circuit responsive to the seizure of a calling line for actuating said switching means to establish a connection from said calling line to an idle link circuit and to an idle register circuit, means responsive to dial pulses received over said calling line for recording said impulses in said register, means operative when said impulses have been recorded for causing said register to control said marker circuit to select an idle junctor circuit and connect said idle junctor circuit to the called line through said switching means, connect said idle junctor circuit to said seized link circuit through said switching means, connect an idle ringing circuit to said junctor circuit through said switching means, and to cause said ringing circuit to transmit ringing current to said called line in accordance with recorded impulses and release said marker circuit, and means operated when the called subscriber answers a call for releasing said ringing circuit from said junctor circuit.

3. In a telephone system, calling lines, called lines, switching means, link circuits, junctor circuits, register circuits, ringing circuits, a marker circuit responsive to the seizure of a calling line for actuating said switching means to establish a connection from said calling line to an idle link circuit and to an idle register circuit, means responsive to dial pulses received over said calling line for recording said impulses in said register, means operative when said impulses have been recorded for causing said register to control said marker circuit to select an idle junctor circuit and connect said idle junctor circuit to the called line through said switching means, connect said idle junctor circuit to said seized link circuit through said switching means, connect an idle ringing circuit to said junctor circuit through said switching means, means for thereafter causing said ringing circuit to transmit ringing current to said called line in accordance with recorded impulses and for causing said register and said marker circuits to release, means operative when the called subscriber answers for releasing said ringing circuit from said junctor circuit.

4. In a telephone system, calling lines, switching means, register circuits, trunks, links and by-links, a marker circuit responsive to the seizure of a calling line for actuating said switching means for establishing a connection from said calling line through an idle link to an idle register circuit, means responsive to dial pulses received over said calling line for recording said impulses in said seized register, means operative when said impulses have been recorded for connecting a corresponding trunk through a by-link to the seized register circuit, and means operative while said connection to the trunk is being established for causing said marker circuit to connect said trunk through said switching means over said seized link to the calling subscriber's line and to release said by-link, said register and said marker circuit.

5. In a telephone system, calling lines, switching means, register circuits, trunks, links and by-

links, a marker circuit responsive to the seizure of a calling line for actuating said switching means for establishing a connection from said calling line through an idle link to an idle register circuit, means responsive to a first series of dial pulses representing a digit and succeeding series of dial pulses representing succeeding digits received over said calling line for recording said impulses in said seized register, means operative when said first series of dial pulses have been recorded for connecting a corresponding trunk through a by-link to the seized register circuit, means operative while said connection to the trunk is being established for causing said marker circuit to connect said trunk through said switching means over said seized link to the calling subscriber's line and to release said by-link, said register and said marker circuit and means for transmitting said succeeding series of impulses over the first-mentioned connection to said trunk and over said second-mentioned connection to the trunk when established in case the transmission of said succeeding series of impulses has not been completed before the first-mentioned connection is released.

6. In a telephone system, lines, trunks, switching means, links, by-links, registers, means for establishing a connection from a calling line to a register over an idle link and said switching means and for then establishing a connection from said seized register to a trunk over a by-link, means for thereafter establishing a connection from the calling line over the seized link to said trunk through said switching means and for releasing said register and by-link, means for establishing a connection from a trunk to a by-link to an idle register, means for thereafter establishing connections from said last-mentioned trunk to said last-mentioned register over an idle link through said switching means and for releasing the connection from said last-mentioned trunk through a by-link and means for thereafter establishing connections over said switching means from the last-mentioned trunk over the associated link to a called line and for releasing said last-mentioned register.

7. In a telephone system, lines, trunks, linking and switching means, by-links, register circuits, ringing circuits, means operative when a call is made from a calling line for establishing a connection from said calling line to a called line over said linking and switching means or for establishing a connection from said calling line to a trunk over said linking and switching means and a by-link, for then releasing said connection through said by-link after an interval and for establishing the connection from said calling line to said trunk directly over said linking and switching means, means for establishing a connection directly from a trunk over a by-link to an idle register, means for then establishing a

- connection from said last-mentioned trunk after an interval to said register over said linking and switching means and for releasing the connection through the by-link and for thereafter establishing connections over said linking and switching means from said trunk to a called line and for releasing said register, means operative when a connection has been established through to a called line from either a calling line or from a trunk for associating an idle ringing circuit with the called line over said linking and switching means and for ringing the called line from said ringing circuit, and means responsive when the subscriber of the called line answers for releasing said ringing circuit.
8. In a telephone system, a called line, switching means, register circuits, trunks, links and by-links, means responsive to the seizure of a trunk for establishing a connection over a by-link to an idle register circuit, means responsive to dial pulses received over said trunk for transmitting said dial pulses over said link and recording them in said seized register, a marker circuit responsive on the seizure of said register for actuating certain of said switching means to connect said trunk through an idle link to said seized register and release the connection between said trunk and register through said by-link, means for actuating said marker circuit responsive to said recorded impulses in the register for establishing a connection through certain other switching means to a calling line from said trunk over said seized link, and means for thereafter releasing said marker circuit and said register.
9. In a telephone system, a called line, switching means, register circuits, trunks, links and by-links, means responsive to the seizure of a trunk for establishing a connection over a by-link to an idle register circuit, means responsive to dial pulses received over said trunk for transmitting said dial pulses over said link and for recording them in said register, a marker circuit responsive to the seizure of said register for actuating certain of said switching means to connect said trunk through an idle link to said seized register and release the connection between said trunk and register through said by-link, means operated when the register has been connected to said trunk through said link for continuing the transmission of impulses to said register from said trunk over said link in case succeeding impulses are received after the connection through the by-link is opened, and means for actuating said marker circuit in response to the recorded impulses in the register for establishing a connection through certain other switching of said switching means to a called line from said trunk over said seized link, and means for thereafter releasing said marker circuit and said register.

EDSON L. ERWIN.

FREDERICK R. LAMBERTY.
